BUILDING FORMED OF BLOCKS

Albert E. Eitemiller and Harriett J. Eitemiller,
Medford, Oreg.

Application November 17, 1952, Serial No. 22,324

Term of patent 7 years

(Cl. D34—15)

To all whom it may concern:

Be it known that we, Albert E. Eitemiller and Harriett J. Eitemiller, citizens of the United States, residing at Medford, State of Oregon, have invented a new, original, and ornamental Design for Building Formed of Blocks, of which the following is a specification, reference being had to the accompanying drawing, forming a part thereof.

Fig. 1 is a perspective view of a building formed of blocks and showing my ornamental design.

Fig. 2 is a perspective view of the building shown in Fig. 1 as seen from the side of the house opposite the view of Fig. 1.

We claim:

The ornamental design for a building formed of blocks, as shown and described.
